US0D1008023S

(12) **United States Design Patent** (10) **Patent No.:** **US D1,008,023 S**
(45) **Date of Patent:** **** Dec. 19, 2023**

(54) **SUSPENDABLE DUNNAGE**

(71) Applicant: **Signode Industrial Group LLC**,
Glenview, IL (US)
(72) Inventor: **Humberto Laguna**, Chowchilla, CA
(US)
(73) Assignee: **Signode Industrial Group LLC**,
Tampa, FL (US)
(**) Term: **15 Years**
(21) Appl. No.: **29/726,798**
(22) Filed: **Mar. 5, 2020**
Related U.S. Application Data

(63) Continuation of application No. 16/242,342, filed on
Jan. 8, 2019, now abandoned.

CLAIM

The ornamental design for a suspendable dunnage, as shown and described.

DESCRIPTION

FIG. 1 is a front perspective view of a suspendable dunnage of my new design.

FIG. 2 is a back perspective view of the suspendable dunnage of FIG. 1.

FIG. 3 is a front elevational view of the suspendable dunnage of FIG. 1.

FIG. 4 is a back elevational view of the suspendable dunnage of FIG. 1.

FIG. 5 is a top plan view of the suspendable dunnage of FIG. 1.

FIG. 6 is a bottom plan view of the suspendable dunnage of FIG. 1.

FIG. 7 is a right-side elevational view of the suspendable dunnage of FIG. 1; and,

FIG. 8 is a left-side elevational view of the suspendable dunnage of FIG. 1.

The broken lines form no part of the claimed design.

1 Claim, 3 Drawing Sheets
